THERMOSTATIC CONTROL

Original Filed Sept. 14, 1927

UNITED STATES PATENT OFFICE

HARRY HERTZBERG, OF BROOKLYN, NEW YORK, ASSIGNOR TO FRANK J. KENT, OF NEW YORK, N. Y., AND HIMSELF, JOINTLY

THERMOSTATIC CONTROL

Application filed September 14, 1927, Serial No. 219,405. Renewed June 10, 1931.

This invention relates to a thermostatic control for electrical heating elements and provides a circuit breaker for preventing excessive temperature in the heating elements.

5 The invention is particularly useful in connection with electrical flat-irons, since the use of such irons creates peculiar problems that are most efficiently solved by the apparatus disclosed herein.

10 An object of the invention is to provide a thermostat that will break the circuit positively and quickly after the temperature of the apparatus has passed above the critical point.

15 The invention also includes the provision of a heating relay for the thermostat, the relay being so arranged that a slight initial movement of the thermostatic element brings into operation the heating relay which applies heat directly to the thermostatic element and hastens the operation of breaking the circuit to the heating element of the iron, or other apparatus.

20 Other features of the invention cooperate to produce a compact and simple device that is positive in operation and having a long useful life.

25 While a preferred form of the invention has been disclosed for purposes of illustration, it should be understood that various changes may be made in the structure without departing from the spirit and scope of the invention as hereinafter set forth and claimed.

30 In the drawings;

Fig. 1 is a side elevation of a flat-iron equipped with a connector plug embodying the invention.

35 Fig. 2 is a section through the connector plug showing the parts in position to supply current to the heating element of the iron.

40 Fig. 3 is a view similar to Fig. 2, showing an intermediate position of the thermostat.

45 Fig. 4 is a section showing the parts after

the thermostat has broken the circuit to the heating element.

Fig. 5 is a section taken at right angles to Fig. 2.

Fig. 6 is a perspective of the thermostat.

50 Fig. 7 is an enlarged detail of one end of the thermostat.

55 Referring to the drawings more particularly, the reference numeral 1 designates the casing of the connector plug, which is formed of insulating material in a well-known manner. An aperture 2 provides entrance for the feed wires 3, 3, which are attached to binding posts 4 and 5. The opposite end of the plug carries spring sockets 6, 6, for cooperation with the posts 7, 7 of the iron. One of the sockets 6 is connected by a conductor 8 with binding post 4, and the conductor 8 carries a lip 9 projecting inwardly and downwardly from the binding post 4. The other socket 6 is connected by a conductor 10 with the post 11 on which is pivoted the knife switch 12. The outer end of the knife switch extends through a slot 13 in the casing and carries an insulating button 14. The inner end of knife switch 12 cooperates with a clip 15 mounted on the binding post 5. A spring 16 engages a finger 17 formed on knife switch 12 and a finger 18 formed on the lower end of the conductor 10, and normally biases the switch arm 12 away from the clip 15. The switch arm 12 is held in contact with the clip 15 by a thermostat 19, which will now be described.

60 The thermostat, shown in detail in Figs. 6 and 7, comprises a strip 20 of any suitable structure, being preferably formed of two metals having different co-efficients of thermal expansion, according to well-known construction. This strip 20 is formed so that 65 when cold it assumes a V-shape as shown in Fig. 6. A heating element, which is attached to the inner side of an arm of the thermostat, includes a wire-wound resistance core 21 and insulating strips 22 of mica or other suit- 70 75 80 85 90

able material. Metallic rivets 23, and 23a secure the insulating strips to the resistance core and each rivet is in contact with one end of the wire of the core. The heating element is secured to the strip 20 by a clip 24 and a band of insulation 25. The strip 20 terminates at the outer end of insulation 25, as will be clear from Fig. 7, so that the circuit through the resistance core 21 passes from rivet 23 to winding 21, to rivet 23a, and thence to arm 20.

The thermostat is mounted in the connector plug by having the eyelet 26, formed at the juncture of its arms, pivotally engaged over a screw post 27 placed between the spring sockets 6, 6, the parts being so arranged that in the normal operating position (Fig. 2) the left arm of the thermostat presses clip 24 against the conductor 8, while the right arm engages a notch 28 in the lower side of the knife switch 12 to hold the switch in contact with clip 15. In this position of the parts current flows to the posts 7, 7 of the iron, but no current flows through the heating element of the thermostat, due to the fact that the left arm of the thermostat is separated from the conductor 8 by the insulation 25.

If at any time during the use of the flat iron its temperature goes above a certain pre-determined danger point, the arms of the thermostat immediately begin to converge, causing the left arm to move from the position of Fig. 2 to the position of Fig. 3, causing the rivet 23 to make contact with the lip 9. As soon as this occurs current flows through the resistance wire of the heating element 21, which applies a strong local heating effect along the entire length of the left arm of the thermostat, and quickly causes further contraction of the thermostat until the right arm becomes disengaged from the notch 28 and finally reaches the full line position of Fig. 4. This action, of course, breaks the circuit between binding post 5 and conductor 10, as well as that through the heating element 21.

Due to the fact that the arms of the thermostat are contracted against opposite sides of lip 9, the right arm is out of the path of the knife switch 12, and it is impossible to immediately reset the switch to send current through the heating element of the iron. Before resetting it is necessary to permit the iron to cool until the thermostat relaxes to the dotted position of Fig. 4, at which time the switch can again be placed in the normal operative position of Fig. 2.

The structure set forth above has a number of important advantages. The provision of a V-shaped pivoted thermostat permits the use of a relatively long length of thermostatic material while still preserving the proportions of the conventional connector plug. This arrangement of the thermostat also per-

mits the location of its operative ends at points remote from the sockets 6, 6, which is a factor making for a compact arrangement.

The provision of the heating relay 21 causes the thermostat to break the circuit after the temperature of the iron has risen only a short distance above the danger point. This is because only a small rise in temperature is needed to move the left arm of the thermostat from the position of Fig. 2 to that of Fig. 3. From this point the heating relay rapidly boosts the temperature of the thermostat and causes prompt severance of the main circuit through the plug.

In addition to these advantages the device has certain features of rugged and simple construction and ease of assembly that will be evident to those skilled in the art.
